FOLDING ROLLER SUPPORT

Henry A. Wise Wood, New York, N. Y., assignor
to Wood Newspaper Machinery Corporation,
New York, N. Y., a corporation of Virginia

Application March 31, 1928, Serial No. 266,229
Renewed May 22, 1931

15 Claims. (Cl. 270—77)

This invention relates to supporting means for the folding rollers of a folding machine.

The principal objects of the invention are to provide an improved adjustable means for controlling the distance between the folding rollers to enable them to operate upon folded products of different thicknesses; to provide the two folding rollers with means whereby, when a choke occurs, one of the rollers will automatically fall out of position, permitting the papers to be cleared out; and to provide this means in such form that the rollers can be replaced very readily in their original position without changing their adjustment.

15 Other objects and advantages of the invention will appear hereinafter.

Reference is to be had to the accompanying drawings, in which

Fig. 1 is an end view of a folding couple with the folding rollers supplied with a preferred embodiment of this invention;

Figs. 2 and 3 are diagrammatic end views showing the adjustment for products of different thicknesses;

25 Fig. 4 is a plan of the supporting means for one end of the folding rollers;

Fig. 5 is a similar view showing the other end;

Fig. 6 is an end view of Fig. 4;

30 Fig. 7 is a side elevation of the same showing the frame of the machine in section;

Fig. 8 is an enlarged end elevation like Fig. 1, showing the adjusting means;

Fig. 9 is a plan of the adjusting screw and its 35 connected parts;

Fig. 10 is a plan, partly in section, of the means for adjusting the two ends of one of the rolls;

Fig. 11 is a end view of the dial shown in Fig. 40 8; and

Fig. 12 is an end view of the gearing for running the two folding rolls.

The most frequent chokes in a newspaper folder occur in the folding rolls. It is important, 45 therefore, to provide the greatest practicable amount of clearance between the folding rolls and the folding cylinder when a choke occurs at that point, so that the papers may be ejected therefrom without bending the folding roller shafts or breaking any of the other parts. It is for this purpose that this invention is made.

I have shown the invention as applied to an ordinary folding couple, comprising the folding cylinder 10, the cutting cylinder 11, and folding 55 rolls 12 and 13. These folding rolls are indi-

rectly supported at each end by brackets 14 and 14^a which are pivoted on studs 15 carried by the frame 16 of the machine. Each bracket 14 and 14^a carries at the side a pivot stud 17 on which is pivotally mounted a swinging bracket 18 which is the real support for the folding roller shaft. Each swinging bracket 18 is located, of course, on the inner side of the bracket 14 or 14^a and carries ball-bearings for the end of the folding roll shaft.

60 Each bracket 18 is normally fixed to the pivoted bracket 14 or 14^a by a shear pin 19, and in ordinary operation these two brackets act as one. Each bracket 14 and 14^a is provided with a stop pin 20, against which the bracket 18 engages 70 when it drops down due to the shearing of the pin 19. This occurs when a choke of paper exerts enough pressure on the folding roll to break the pins at both ends.

75 The pin 19 is held in place by a set screw 21 and can be taken out when broken and replaced by a new one very readily to set the roll back in the position which it previously occupied and without any change of the adjustment.

80 The folding rolls are driven by a gear 22 on the folding cylinder shaft meshing with a gear 23 on the shaft of the folding roll 13. On this shaft is a gear 24 which, in turn, meshes with a gear 24^a of the same size on the shaft of the folding roll 12.

85 The folding roll supports are made the same way at both ends of each folding roll, and the same way, but of the opposite hand, at the ends of the two rolls. The brackets 14 and 14^a are provided with open-ended slots 25 and 26 for receiving studs 27 and 27^a on a pair of nuts 28, threaded right and left hand. These nuts receive an adjusting screw 29 which has a right and left hand thread, so that upon turning the screw 90 the rolls are moved toward or from each other.

95 Behind the bracket having the slot 26 is a spring 30 on the adjusting screw 29 held in position by a nut and check-nut 31 for holding the bracket 14 yieldingly against the stud 27 in the slot 26. The other slot 25 is vertical and therefore positive.

100 On each of the adjusting screws 29 is an adjusting sleeve 32 threaded into a hole in the frame. It can be moved out and in, being provided with spanner holes 33 for that purpose, and with a check nut 34.

105 On the end of the screw 29 is a dial 35 numbered in accordance with the conditions existing, and a stationary zero point 36 is carried by the frame. This provides a reading to show how far

- apart the folding rolls are adjusted and it is calibrated to show how many double thicknesses of paper the rolls will receive between them, i. e. the number of sheets.
5. Of course it will be understood that the two ends of both rollers should be adjusted alike ordinarily, and for that reason each one of the two adjusting screws 29 is provided with a gear or toothed wheel 38. A shaft 39 extends across the machine 10 having two worms or gears 40 meshing with the gears 38, and when they are both turned alike will adjust the two screws 29 alike.
- One of these worms is fixed to the shaft 39 and the other is rotatable thereon but fixed to a sleeve 15 41. On the sleeve is a hand wheel 42 and on the shaft 39 is a hand wheel 43. Therefore these two hand wheels can be turned together very conveniently or one of them turned separately to line up the rolls.
20. In this way it will be seen that when a choke occurs one of the shear pins will break. This allows the roll to fall down as indicated in dotted lines in Fig. 6 and permits of clearing the papers away from the folder without bending the folding roll shafts or injuring any of the parts. When this is done, the roll is moved up to its normal position and the shear pins replaced, all without any change in the adjustment of the distance between the folding rolls.
30. Although I have illustrated and described only a single form of the invention, I am aware of the fact that changes can be made therein by any person skilled in the art without departing from the scope of the invention as expressed in the 35 claims. Therefore, I do not wish to be limited to the exact form shown, but what I do claim is:—
1. In a folding couple comprising a pair of folding rolls, the combination of a pair of movable supporting brackets, means for adjusting them, 40 brackets movably carried by the first named brackets and having bearings for the ends of the folding rolls, and frangible means for normally holding the last named brackets in fixed position relative to said adjustable brackets.
45. 2. In a folding couple comprising a pair of folding rolls, the combination of a pair of pivoted supporting brackets, means for adjusting them simultaneously in opposite directions about their pivots, brackets pivotally carried by the first named brackets and having bearings for the ends of the folding rolls, and frangible means for normally holding the last named brackets in fixed position relative to said adjustable brackets.
50. 3. In a folding couple comprising a pair of folding rolls, the combination of a pair of pivoted supporting brackets, means for adjusting them simultaneously in opposite directions about their pivots, brackets pivotally carried by the first named brackets and having bearings for the ends of the folding rolls, and frangible means for normally holding the last named brackets in fixed position relative to said adjustable brackets, the pivots for the last named brackets being located 55 farther apart than and on opposite sides of the axes of the bearings.
60. 4. In a folding couple comprising a pair of folding rolls, the combination of a pair of pivoted supporting brackets, means for adjusting them simultaneously in opposite directions about their pivots, brackets pivotally carried by the first named brackets and having bearings for the ends of the folding rolls, and frangible means for normally holding the last named brackets in fixed position 65 relative to said adjustable brackets, a right and left hand adjusting screw for the two supporting brackets at one end of the rolls, positive means for connecting one bracket with the screw and yielding means for connecting the other bracket with the screw.
5. In a folding couple comprising a pair of folding rolls, the combination of a pair of pivoted supporting brackets, means for adjusting them simultaneously in opposite directions about their pivots, brackets pivotally carried by the first named brackets and having bearings for the ends 80 of the folding rolls, frangible means for normally holding the last named brackets in fixed position relative to said adjustable brackets, a right and left hand adjusting screw for the two supporting brackets at one end of the rolls, said screw being longitudinally adjustable by turning it, and a dial operated by the screw and calibrated to show how many folds of paper can be passed between the rolls in any adjusted position.
6. In a folding couple comprising a pair of folding rolls, the combination of a pair of pivoted supporting brackets, means for adjusting them simultaneously in opposite directions about their pivots, brackets pivotally carried by the first named brackets and having bearings for the ends 85 of the folding rolls, frangible means for normally holding the last named brackets in fixed position relative to said adjustable brackets, said frangible means consisting of a shear pin, and a stop on each supporting bracket for the last named 90 bracket.
7. In a folder, the combination of a pair of adjustable brackets on opposite sides of the folder, a pair of brackets each pivotally supported by one of the adjustable brackets, shear pins for fixing each of the second brackets to one of the adjustable ones, and bearings for the opposite ends of a folding roll on the second brackets, whereby when a choke occurs and the pins are broken the roll can swing out of position.
8. In a folding machine, a pair of folding rolls, a folding blade adapted to tuck a sheet into the bite of the said rolls for the purpose of folding it, resilient means for permitting the rolls to yield slightly during the folding operation, and suddenly releasable means normally holding one of the rolls with respect to said resilient means but adapted to act to free one of the said rolls and permit it to release the sheet in the event of a paper choke which would otherwise require the 100 rolls to be suddenly separated a greater distance than that for which they are set for normal operation.
9. A folding mechanism including in combination a folding cylinder, a pair of folding rollers, 105 means carried by said cylinder for folding a group of sheets between said rollers and means normally holding said rollers unyielding and adjacent to the folding cylinder and automatically releasing said rollers under excessive strains to move 110 the rollers away from the folding cylinder.
10. A folding mechanism including in combination a pair of folding rollers, means for folding a group of sheets between said rollers and means normally holding said rollers adjacent to the folding cylinder and automatically permitting free movement of said rollers independently of each other under excessive strains to move the rollers 115 away from the folding cylinder.
11. A folding mechanism including in combination a folding cylinder, a pair of folding rollers, means carried by said cylinder for folding a group of sheets between said rollers, pivoted arms at either end of said rollers, pins for each arm nor- 120

20 mally holding said rollers in folding relation but releasing said rollers on choked folds.

25 12. A folding mechanism including in combination a pair of folding rollers, means for folding a group of sheets between said rollers, pivoted arms at either end of said rollers, pins normally holding said rollers in folding relation but independently releasing said rollers on choked folds.

10 13. A folding mechanism including in combination a pair of folding rollers, means for folding a group of sheets between said rollers and means normally holding said rollers adjacent to the folding cylinder but automatically permitting free movement of said rollers independently of each 15 other under excessive strains to move the rollers away from the folding cylinder, one of said rollers being yieldably mounted.

14. A folding mechanism including in combination a folding cylinder, a pair of folding rollers, means carried by said cylinder for folding a group of sheets between said rollers and means normally holding said rollers adjacent to said cylinder but automatically permitting free movement of them independently of each other on choked folds, one of said rollers being yieldably mounted.

80 15. A folding mechanism, including in combination a pair of folding rollers, means for folding a group of sheets between said rollers, pivoted arms in which said rollers are rotatably mounted at their ends and removable pins normally holding said rollers individually in folding relation, but permitting said rollers to be moved away from each other.
